UNITED STATES PATENT OFFICE.

OSCAR T. BACKLUND, OF DEER LODGE, MONTANA.

MUFFLER CUT-OUT.

Application filed February 9, 1923. Serial No. 618,031.

To all whom it may concern:

Be it known that OSCAR T. BACKLUND, a citizen of the United States of America, residing at Deer Lodge, in the county of Powell and State of Montana, has invented new and useful Improvements in Muffler Cut-Outs, of which the following is a specification.

The object of the invention is to provide 10 an efficient muffler cutout for automobiles and similar motor-driven vehicles and particularly to provide a device of this type which may be applied with facility to the exhaust pipes of automobiles already in use 15 and therefore which is adapted to be produced and handled as an accessory; and with these objects in view the invention consists in a construction and combination of parts of which a preferred embodiment is shown 20 in the accompanying drawings, wherein:—

Figure 1 is a side view of a cutout mechanism constructed in accordance with the invention applied in the operative position to a motor exhaust.

Figure 2 is a sectional view of the motor exhaust pipe showing in full and dotted lines respectively the cutout in its operative and inoperative positions.

Figure 3 is a transverse sectional view on 30 a plane indicated by the line 3—3 of Figure 1.

Figure 4 is a detail perspective view of the extremity of the operating lever connected with the valve.

The device is applicable to a motor exhaust pipe 10 of the ordinary construction usually communicating with or terminating in a muffler 11 or its equivalent, and in preparation for the application thereto of the 40 cutout this exhaust pipe is provided with an outlet opening 12 to which is fitted a valve 13 of approximately pear shape and having a transverse curvature corresponding with that of the exhaust pipe. The outlet opening of the exhaust pipe is preferably of a 45 similar shape but slightly smaller than the valve so that when the valve is in its normal or closed position it serves to prevent exhaust through said outlet and cause the exhaust from the motor to pass to the muffler as in the ordinary practice.

The valve is provided at a point intermediate of its length with a slot 14 through 55 which extends one end of an operating lever 15 engaged at the inner surface of the valve by a cotter pin 16 or its equivalent and

provided outside of the plane of the valve with a stop shoulder 17. The base or broadest portion of the valve is of a width approximately equal to the interior diameter 60 of the exhaust pipe and therefore when the operating lever is swung upon its pivotal point or axis 19 to move the valve from its inoperative or closed position to its operative or outlet opening position, the valve 65 without other attachment to or mounting in the exhaust pipe swings upon a center represented by the broadest portion of its base to assume an oblique position in the exhaust pipe as shown by the full lines in Figure 2. 70

The operating lever is mounted upon a bolt constituting the pivot or axis 19 which is carried by a bracket or clamp 20 embracing the exhaust pipe and held in place by a clamping bolt 21, and said lever is yieldingly 75 held in a position to maintain the valve in the closed or inoperative position by a spring 22 connecting said clamp with the free end of the lever, and operatively connected with said free end of the lever is a 80 push rod 23 having a knob or table head 24 exposed within convenient reach of the operator as adjacent to the foot board of the car. Also in this connection as a means of holding the cutout in the open position a 85 catch plate 26 may be employed to form a guide for the push rod which may be fitted with a shoulder 27 for engagement therewith when the button or table is depressed to open the outlet. 90

Having described the invention, what is claimed as new and useful is:—

1. A muffler cutout having in combination with an exhaust pipe provided with a lateral outlet opening, a valve loosely fitted in 95 the pipe, an operating lever loosely connected with the valve for movement diametrically of the pipe, and operating means for said lever, the valve being of pear shape with its maximum width corresponding substantially with the diametrical dimension of the exhaust pipe. 100

2. A muffler cutout having in combination with an exhaust pipe provided with a lateral outlet opening, a valve loosely fitted in 105 the pipe, an operating lever loosely connected with the valve for movement diametrically of the pipe, and operating means for said lever, the valve being of pear shape with its maximum width corresponding substantially with the diametrical dimension of the exhaust pipe, and the operating lever 110

having a loose connection therewith to permit of rocking movement of the valve with relation thereto.

3. A muffler cutout having in combination 5 with an exhaust pipe provided with a lateral outlet opening, a valve loosely fitted in the pipe, an operating lever loosely connected with the valve for movement diametrically of the pipe, and operating means 10 for said lever, the valve being of pear shape with its maximum width corresponding substantially with the diametrical dimension of the exhaust pipe, and the operating lever having a loose connection therewith to permit 15 of rocking movement of the valve with relation thereto, said lever being provided with a stop shoulder for contact with the exterior surface of said valve.

4. A muffler cutout having in combination 20 with an exhaust pipe provided with a lateral outlet opening, a valve loosely fitted in the pipe, an operating lever loosely connected with the valve for movement diametrically of the pipe, and operating 25 means for said lever, the valve being transversely arched to correspond with the diameter of the exhaust pipe and being sub-

stantially pear shaped with its greatest width approximating the diametrical dimension of the said pipe, and the operating 30 lever having a terminal extended through an opening in said valve and fitted with a cotter pin.

5. A muffler cutout having in combination 35 with an exhaust pipe provided with a lateral outlet opening, a valve loosely fitted in the pipe, an operating lever loosely connected with the valve for movement diametrically of the pipe, and operating means 40 for said lever, the valve being transversely arched to correspond with the diameter of the exhaust pipe and being substantially 45 pear shaped with its greatest width approximating the diametrical dimension of the said pipe, and the operating lever having a 50 terminal extended through an opening in said valve and fitted with a cotter pin, and a stop shoulder for contact respectively with the inner and outer surfaces of the valve.

In testimony whereof he affixes his signature.

OSCAR T. BACKLUND.
